VEHICLE DOOR PANEL OR SIMILAR
ARTICLE

John H. Spence, Chicago, Ill., assignor to Pullman-Standard Car Manufacturing Company, Chicago, Ill., a corporation of Delaware

Application March 17, 1951, Serial No. 14,526

Term of patent 14 years

(Cl. D66—2)

To all whom it may concern:

Be it known that I, John H. Spence, a citizen of the United States of America, and resident of Chicago, county of Cook, and State of Illinois, have invented a new, original, and ornamental Design for Vehicle Door Panel or Similar Article, of which the following is a specification, reference being had to the accompanying drawings, forming part thereof.

In the drawings:

Fig. 1 is a general elevational view of my new design of vehicle door panel;

Fig. 2 is a vertical cross sectional contour view taken on the line 2—2 of Fig. 1;

Fig. 3 is a horizontal cross sectional contour view taken on the line 3—3 of Fig. 1;

Fig. 4 is a general perspective view of one of the embossed panels making up my new design of vehicle door panel;

Fig. 5 is an outside elevational view of the door panel shown in Fig. 4;

Fig. 6 is a vertical cross sectional contour view of the door panel taken on the line 6—6 of Fig. 5; and

Fig. 7 is a horizontal cross sectional contour view of the door panel taken on the line 7—7 of Fig. 5.

What is claimed is:

The ornamental design for a vehicle door panel or similar article, substantially as shown.

JOHN H. SPENCE.
